[57] **CLAIM**

The ornamental design for a front bezel for a rack mounted disk storage subsystem of a data processing system, as shown and described.

DESCRIPTION

FIG. 1 is a top, front, right side isometric view of a front bezel for a rack mounted disk storage subsystem of a data processing system showing our new design; FIG. 2 is a front elevational view thereof on an enlarged scale;

FIG. 3 is a right side elevational view thereof; and, FIG. 4 is a top plan view thereof.

The left side of the bezel is identical to the right side shown in FIG. 3. The bottom and rear are unornamented.

FIG. I

FIG. 2

FIG. 3

FIG. 4
